RAZOR BLADE SHARPENER

Filed Aug. 25, 1931

FIG 1.

FIG 2.

Inventor

H. J. Linn

Watson E. Coleman
Attorney

UNITED STATES PATENT OFFICE

HENRY J. LINN, OF ZANESVILLE, OHIO.

RAZOR BLADE SHARPENER

Application filed August 25, 1931. Serial No. 559,255.

This invention relates to devices for sharpening razor blades and more particularly to devices for truing the edge of a razor blade. When a razor blade is stropped or honed, 5 the last stroke of the blade on the hone acts to push the fine saw teeth formed on the edge of the blade sidewise and in order that the razor blade will cut properly, it is necessary that these burrs or teeth shall be straightened 10 up.

The object, therefore, of my device is to provide means whereby these fine saw tooth edges may be straightened after the razor 15 blade is honed and thus the razor blade put into proper shape for use.

A further object is to provide a device of this character which is very simple, may be cheaply made and has been found thoroughly effective for the purpose intended.

20 My invention is illustrated in the accompanying drawing wherein:—

Figure 1 is a perspective view of a razor blade sharpener constructed in accordance with my invention;

25 Figure 2 is a diametric section therethrough.

In this drawing, 10 designates a body of cork or like material. I have found, however, that cork is the best material that I can 30 use for the purpose.

This body of cork is illustrated as cylindrical in form and the periphery of this cylindrical body is formed with a V-shaped circumferentially extending groove or notch 35 designated 11. This groove 11 is preferably one-sixteenth of an inch wide and one-eighth of an inch deep and, as before stated, is approximately V-shaped in cross section. The groove is disposed at equal distances from the 40 side faces of the cork body. Disposed on each side of the cork body are the preferably metal plates 12 whose edges may be flanged slightly as at 13 and turned over upon the peripheral face of the cork body. These 45 plates 12 are held in place against the cork body by means of the rivet 14 extending entirely through the body and plates. A binding, 15 preferably of heavy paper or like material is extended circumferentially 50 around the cork body on each side of the

slot 11. After the groove in the body is formed, the surface of the groove is preferably painted with tincture of iodine which helps preserve the surface of the slot or 55 groove from disintegration and also acts as a disinfectant to the blade that is drawn through it. The iodine also acts to some extent to harden the cork. The metal side pieces 12 are to hold the cork in place and prevent it from breaking up or disintegrating, but while I preferably use metal, stiff 60 cardboard glued to the cork can also be used in place of this metal. The bands 15 of paper that are glued around the circumference of the sharpener prevent the surface of the cork from disintegrating and they act also 65 as a sort of guide for the blade.

While metal might be used, stiff paper is 70 preferable as there is then no chance of the edge of the blade striking accidentally against the metal and becoming dull. It is to be understood that there are no abrasive surfaces on this razor blade, truer or sharpener, but that the edge of the blade is sharpened or trued simply by drawing it through or in 75 the groove 11. The cork being somewhat resilient, acts to straighten the sharp saw teeth on the edge of the blade so as to bring them all in line and thus put the razor in 80 good condition for use.

I claim:—

1. A razor blade sharpener of the character described, comprising a cylindrical body of cork having in its circumference a V-shaped groove through which the edge of a razor blade may be drawn, and relatively stiff end members disposed against the sides of the cylindrical body to prevent the disintegration 85 of the cork.

2. A razor blade sharpener of the character described, comprising a cylindrical body of cork having in its circumference a V-shaped groove through which the edge of the razor blade may be drawn, relatively stiff end members disposed against the sides of the cylindrical body to prevent the disintegration 90 of the cork, and bands extending around the circumference of the body on each side of said groove.

3. A razor blade sharpener of the character 100

ter described, comprising a cylindrical body of cork having in its circumference a V-shaped groove through which the edge of the razor blade may be drawn, relatively stiff end members disposed against the sides of the cylindrical body to prevent the disintegration of the cork, and paper bands extending around the circumference of the body on each side of the groove.

10 4. A razor blade sharpener of the character described comprising a cylindrical body of cork having in its circumference a V-shaped groove, the groove being deeper than it is wide, the walls of the groove being treated with a hardening and disinfecting agent, side plates attached to the sides of the body, and paper bands attached to the periphery of the body on each side of said groove.

15 In testimony whereof I hereunto affix my
20 signature.

HENRY J. LINN.
